PUMPING APPARATUS

Wade H. Wineman, Michigan City, Ind., assignor
to Sullivan Machinery Company, a corpora-
tion of Massachusetts

Application September 17, 1940, Serial No. 357,155

13 Claims. (Cl. 255—16)

This invention relates to pumping apparatus, and more particularly to apparatus for yieldingly supporting a positively actuated member for raising and lowering a sucker rod connected to a pump in an oil well.

In producing an oil well by a pump located near the bottom of the well and driven through a sucker rod connected to a reciprocating device at the surface, there will be a large increase in the load on the rod during each reversal between its downward and upward strokes. This heavy load repeatedly applied to the sucker rod causes a serious reduction in the life of the rod. The power consumed is more than would be necessary to do the useful work, and the available power necessary is greater than that required if the load was reduced.

It is an object of this invention to provide an improved pumping system. It is another object of this invention to provide an improved pump-actuating apparatus. It is still another object of this invention to provide an improved beam-type pumping system having means for reducing the peak loads on the sucker rod and on the pumping system. Still another object of this invention is to provide an improved supporting structure for the beam of a beam-type pumping system. Another object of this invention is to provide an improved yielding supporting structure for a walking beam having associated therewith means actuated by the walking beam for regulating the yielding resistance offered by said structure. Other objects and advantages of the invention will hereinafter more fully appear.

In the accompanying drawings there are shown for purposes of illustration several forms which the invention may assume in practice.

In these drawings:

Fig. 1 is a side elevational view of a pumping system in which the preferred form of the invention is incorporated.

Fig. 2 is an enlarged vertical sectional view, partially in elevation, through the beam-supporting structure shown in Fig. 1.

Fig. 3 is a vertical sectional view similar to Fig. 2 but showing the parts in different relative positions.

Fig. 4 is a view similar to the lower portion of Fig. 3 but showing a modified form of valve controlled by-pass for returning fluid to the lower side of the piston.

Fig. 5 is an enlarged detail sectional view showing the valve control for the by-pass of Fig. 4.

Fig. 6 is a vertical sectional view through a 55

portion of a modified form of beam-supporting structure.

Fig. 7 is a cross sectional view taken on the plane of the line 7—7 of Fig. 6.

Fig. 8 is a vertical sectional view, with parts in elevation, showing a further modified form of beam-supporting structure.

Fig. 9 is a fragmentary view similar to Fig. 8 showing parts in different relative positions.

Fig. 10 is an enlarged vertical sectional view through a combined oil and air pump employed with the structure shown in Fig. 8.

Fig. 11 is a vertical sectional view through a still further modified form of beam-supporting structure.

Fig. 12 is a vertical sectional view through a modified form of connection between the supporting structure and the walking beam.

Fig. 13 is a sectional view, with parts broken away, taken on the line 13—13 of Fig. 12.

Fig. 14 is a sectional view taken on the plane of the line 14—14 of Fig. 12.

In the illustrative form of the invention shown in Figs. 1, 2 and 3 a "beam" type pumping apparatus, generally designated 1, is connected to a polished rod 2 extending through a casing head 3 of a well and connecting to a sucker rod line (not shown). The pumping apparatus 1 includes a supporting structure, generally designated 4, a walking beam 5, and a driving unit 6 of conventional form connected by a pitman 7 with the walking beam and driven in any suitable manner.

Referring now more particularly to the supporting structure 4 for the walking beam, it will be noted that an upright cylinder 9 rests upon a lower cylinder head 10 and has a bore 11 containing a reciprocable hollow piston 12. Extending upwardly from the piston through a packing 14 in an upper cylinder head 15 is a tube-like piston rod 16 which is closed at its upper end by a wall 17. Threaded onto the upper end of the piston rod is a coupling 18 which receives the threaded end of a cylindrical shaped member 20 journaled at 21 to the walking beam 5 and guided for vertical movement by a sleeve-like member 22 attached to the upper ends of supporting legs 23. A tank 25 containing a gaseous fluid, in this case air, under pressure is connected by a pipe 26 to a passage 27 in the lower cylinder head 10 which opens into a pipe 28 threaded into an opening in the lower cylinder head and extending upwardly into the piston rod.

The diameter of the pipe 28 is such that there is provided between its outer surface and the inner surface of the hollow piston rod, an an-

nular space 29 through which gaseous fluid, conducted from the tank through pipe 26, passage 27 and pipe 28, may pass into the hollow piston 12. In order to seal the gaseous fluid within the tank 25 and its connected passages, and to lubricate the walls of the cylinder bore, there is provided within the lower portion of the cylinder bore a liquid of such a volume that the space within the hollow piston is not quite filled when the piston rests upon the lower cylinder head. As the piston moves upwardly in the cylinder bore the level of the liquid drops, since it then occupies space that had previously been occupied by the walls of the piston, but the length of the bore is such that even when the piston engages the upper cylinder head the lower end of the piston extends below the surface of the liquid a substantial distance and the seal is maintained. Means are provided for cushioning the piston 12 as it moves toward the lower cylinder head, and this means comprises an upwardly projecting portion 30 formed on the lower cylinder head and having a sloping surface 31 which forms an annular space, between the projecting portion and the cylinder wall, of smaller radial dimension at its lower end. A flange 32 formed around the lower end of the piston is received in the annular space and partially entraps liquid to cushion the piston as it moves toward the lower cylinder head.

Breathing means are provided for the upper end of the cylinder bore and include a connection 34 communicating with the bore at a point spaced from the upper end of the cylinder so that a space is provided in the upper end of the bore after the connection 34 is passed, within which fluid may be compressed to cushion upward movements of the piston. The connection 34 opens into a reservoir 35 connected by a hose 36 to a chamber 37 in the lower end of the cylindrical shaped member 20. The chamber 37 communicates through a baffled passage 38 with a larger chamber 39 communicating with atmosphere through openings 40 at its upper end when the piston is in its normal raised position. A connection 42 connects the reservoir 35 with the upper end of the cylinder bore and is provided with a valve 43 which permits fluid flow toward the cylinder bore, thereby preventing the creation of a vacuum in the cylinder as the piston moves downwardly in the space above the connection 34, but the valve 43 prevents any flow of fluid away from the cylinder bore.

It will be noted that the gaseous pressure in the tank and its connected spaces will act against the upper surface of the liquid and against the lower surfaces of the upper end wall of the piston and the wall 17 closing the upper end of the piston rod to urge the piston in an upward direction. The gaseous pressure will be such during normal operation of the pump that the piston will be held in a raised position even with peak loads on the walking beam. The pressure against the surface of the liquid will cause the liquid to be forced gradually between the walls of the piston and the cylinder to the space in the bore above the piston. Means is provided for returning the liquid and a small amount of air with it from the upper to the lower side of the piston when the pressure in the upper end of the cylinder bore exceeds that in the lower end, and this means comprises a valve cage 44 threaded into an opening in the upper wall of the piston and supporting a spring pressed ball valve 45 which controls communication between a passage 46 opening into the upper part of the cylinder bore and a passage opening into a pipe

47 which extends downwardly below the surface of the liquid to provide a seal for the valve. To prevent the pressure in the cylinder beneath the piston from becoming too great, there may be provided a suitable relief valve, not shown, which opens to vent air from the tank 25 and its connected system when the pressure exceeds the desired maximum value. If the pump is shut down for a considerable time all the liquid in the cylinder may eventually be forced to the upper side of the piston, and part of it may flow through the connection 34 to the reservoir 35 and through the hose 36 to the chambers 37 and 39. In order to return the liquid to the lower end of the cylinder bore where it may perform its intended functions there is provided a connection 49 opening into the cylinder bore at a point slightly above the piston when the latter is in its lowermost position and communicating with a passage 50 formed in the lower cylinder head and opening into the lower end of the cylinder bore. A manually controlled throttle valve 51 controls the flow of fluid through connection 49. In order that the liquid may flow freely from the upper to the lower portion of the cylinder bore, the tank 25 and its connected system should be vented to atmosphere by any suitable means. After the liquid has passed into the lower portion of the cylinder, the valve 51 and the venting means are closed, and the tank is repressured by delivering air to it from any outside source.

The mode of operation of the apparatus described will be readily understood from what has been said. Air is supplied to the tank 25 until a pressure is built up within it and its connected system which is sufficient to raise the piston 12 and the walking beam 5 and hold the piston out of contact with the lower cylinder head 10 even when peak loads are carried by the walking beam. As the walking beam is driven by the unit 6 to reciprocate the rod 2 and drive the pump there will be a peak load on the system soon after the unit 6 starts operating on the walking beam to reverse the direction of travel of the rod 2 from a downward to an upward stroke, and the piston 12 will be forced to a low point in the cylinder bore 11. The load will continue to remain heavy during the early portion of the upward stroke, but, as the drive of the walking beam by the power unit 6 slows down, the load on the walking beam will be reduced and the piston 12 will be moved upwardly by the compressed air acting on the lower surface of the upper end wall of the piston and on the lower surface of the wall 17 closing the end of the hollow piston rod 16. The liquid within the lower portion of the cylinder bore prevents the escape of compressed air between the walls of the piston and cylinder, but the pressure of the air upon the liquid will force some of the liquid between these walls to the upper side of the piston. On upward movement of the piston the air in the upper portion of the cylinder bore will be forced through connection 34, reservoir 35, hose 36, chambers 37 and 39 and openings 40 to atmosphere until the piston covers the end of connection 34; then air and liquid above the piston will be entrapped and, due to the inertia of the upwardly moving parts, a pressure will be built up in the space above the piston which is greater than that below the piston; the ball valve 44 will be moved from its seat and the liquid with some air will be forced through pipe 47 to the lower side of the piston. Some of the liquid above the piston will enter connection 34 and

be carried in the form of a mist by the air as it is discharged to atmosphere through openings 40. A portion of the mist will condense at the openings 40 and run down the outer walls of the member 20 to lubricate the sleeve 22.

When the pressure acting on the lower side of the piston 12 is at the proper value, the piston will arrive at the top of its stroke in the cylinder 9 at the same time the driving unit 6 reaches the point where it discontinues its driving of the walking beam to effect an upward movement of the rod 2. The piston will then remain in its uppermost position until the unit 6 operates again on the walking beam to reverse the travel of the rod 2 from a downward to an upward stroke.

Because of the yielding in the supporting structure for the walking beam, the peak loads which are encountered in the conventional beam pumping mechanism are avoided. There is obtained with the yieldable structure not only a great reduction in the rod loads, but also a substantial reduction in the stress range in the rod, and a reduction in the power required to operate the pumping system.

If the pump apparatus is shut down the piston 12 will be held at the upper end of the cylinder bore, but the liquid will seal the lower end of the piston against the escape of compressed air, as shown in Fig. 3. The liquid will be forced gradually around the piston and through connection 34 to the reservoir 35, and in time the level of the liquid will drop below the lower end of the piston; then compressed air will escape from beneath the piston until the pressure is reduced and the piston moves down into the liquid again. Even though an appreciable amount of liquid may have been forced into the reservoir and some of the compressed air may have escaped from under the piston, the apparatus may be restored to its normal operating condition by simply operating the pumping apparatus for a short time. The intermittent application and release of the load on the walking beam causes the piston to reciprocate, and each time the piston moves upwardly some of the liquid above it will be forced past the valve 44 to the lower end of the cylinder. After all the liquid has been returned to the lower side of the piston there will be a small amount of air forced by the valve 44 on each up-stroke of the piston, which will build up the pressure in the tank 25 and its connected passages until released by a suitable safety valve.

If the pumping apparatus remains shut down long enough the liquid will pass above the piston to the reservoir 35 and may flow through the hose 36 to the chambers 37 and 39; then the air pressure below the piston may be so reduced that the piston will not be moved sufficiently to restore the system during pumping operation. To restore the system when this condition exists the pressure remaining in the tank 25 is vented to atmosphere, the valve 51 is opened to drain the liquid through connection 49 into the lower end of the cylinder bore, and then the valve 51 is closed and the tank 25 is repressured.

In Figs. 4 and 5 there is shown a construction similar to that of Figs. 2 and 3 except for the means for conducting fluid from the upper to the lower side of piston 12. Threaded into the upper cylinder head 15 is a valve cage 53 having a portion 54 extending down into the cylinder bore 11 and received within a well 55 formed in the upper surface of the piston 12 when the latter is moved to the upper end of the cylinder bore.

A ball valve 56 is urged by a spring 57 acting against a manually adjustable abutment 58 to prevent normally the flow of fluid from the cylinder bore through a passage 59 to a chamber 60 formed in the valve cage and through a connection 62 opening into the cylinder bore near its lower end. During operation of the pumping system any liquid escaping to the upper side of piston 12 flows into the well 55 and is forced through the passage 59, past the valve 56 to the chamber 60 where it is conducted through connection 62 to the cylinder bore beneath the piston. By adjusting the abutment 58 the valve 56 may be controlled to open at pressures within a range which varies with the strength of spring 57.

Figures 6 and 7 show a cylinder and piston arrangement in which a cylinder 64 is provided with an opening 65 at its upper end for receiving a hollow piston 66, and a packing 67 is pressed into fluid sealing engagement with the piston by a cap 68 suitably secured to the top of the cylinder. Formed in the cylinder is a bore 69 somewhat larger in diameter than the opening 65 and extending from the lower side of the opening to a lower cylinder head 70. A flange 71 formed around the lower end of the piston is slidably received in the bore 69 and is receivable, as explained in the description of Figs. 2 and 3, in an annular space between a projection 72 on the cylinder head and the walls of the bore to partially entrap liquid and cushion the piston. Grooves 74 are formed in the walls of the bore 69 and extend between points spaced a short distance from each end of the bore so that liquid 35 may pass freely between the upper and lower sides of the flange except as it is moved toward either cylinder head at the end of the piston strokes. It will be noted that the upper ends of the grooves have inclined surfaces 75 which provide gradually reducing escape passages for the liquid above the flange as the piston approaches the upper end of its stroke, and thus effect a cushioning of the piston. The cylinder 64 is filled with a liquid to a point such that its level 40 is always above the upper end of the bore 69 and insures the filling of the space above the flange to provide the necessary cushioning action. A suitable gas under pressure is supplied to the space within the hollow piston above the liquid from a connection 26' connected through passage 27' and pipe 28'.

The operation of this modification of the invention is the same as that shown in Figs. 1 to 3 except that the upward strokes of the piston are cushioned by partially entrapping liquid in a space above a flange formed on the piston. Since the liquid and the gaseous fluid are always sealed against escape, it is not necessary that means be provided for restoring the system to normal operating conditions.

In the modification of the invention shown in Figs. 8, 9 and 10, a cylinder 78 is supported in a vertical position by legs 79 and receives in its bore 80 a sleeve-like piston 81 closed at its upper end and having pivotally attached thereto, at 82, a walking beam 83. The cylinder bore is closed at its lower end by a wall 85 and contains a liquid for sealing air under pressure within a space at the upper end of the sleeve-like piston. Any liquid passing between the walls of the piston and cylinder enters an annular groove 87 formed in the walls of the cylinder bore at its upper end and is conducted through a connection 88 to a tank 89. A pump, generally designated 90, is provided for pumping liquid from a hose 91 con-

nected to the tank 89, and for pumping air taken from the atmosphere through a filter 92, into the cylinder bore through a connection 94.

The pump 90 comprises a cylinder block 95 attached, as by bolts 96, to a portion formed on and extending transversely from the upper end of the piston. Formed in the cylinder block are stepped bores 97 and 98 opening into each other, and the larger bore opens through the top of the cylinder block. A piston 100 having portions 101 and 102 receivable, respectively, in the bores 97 and 98 is connected by a link 103 to the walking beam to be driven thereby. The hose 91 opens into a passage 105 controlled by a ball valve 106 and opening into the lower end of the bore 97. A passage 107 in the cylinder block connects the lower ends of the cylinder bores 97 and 98 and is controlled by a ball valve 109. A passage 110 connects the lower end of the cylinder bore 98 to the air filter 92 under the control of a ball valve 111 and to the connection 94 under the control of a ball valve 112. During rocking motion of the walking beam the pump 90 will be operated to pump air continuously from the atmosphere to the cylinder bore and to pump with it any liquid that may have escaped to the tank 89. As the pressure in the cylinder bore increases with the addition of air from the atmosphere the piston is raised, and in order to permit the pressure in the cylinder bore to be released after the piston has been raised a predetermined distance, there is provided a conduit 114 connecting the cylinder bore at a point slightly above the level of the liquid, with the groove 87. In the top of the tank 89 is a vent 115 providing for the escape of air that enters the tank from groove 87 through connection 88.

The mode of operation of this modification of the invention will be clearly apparent from the description given. Liquid may be placed either in the cylinder bore or the tank 89, and then if the pressure in the cylinder is insufficient to support the pumping apparatus the walking beam may be operated without a load until the desired pressure has been built up by the supply of air from pump 90. A load may then be connected to the walking beam and, as the beam is driven, the pump returns to the cylinder any liquid escaping between the cylinder and piston walls to the tank 89 and supplies air from the atmosphere to build up the pressure in the cylinder bore until the piston moves above the lower end of conduit 114 and vents the bore through groove 87, connection 88 and vent 115 in the top of tank 89.

In Fig. 11 there is shown a modification similar to that of Figs. 8 to 10. The cylinder 116 in this modification, however, is supported by a cross member 117 attached to the legs 79 at points below their tops, and reciprocably supported by the cylinder is a piston 118 having extending from its upper end a piston rod 119 reciprocably guided by a sleeve-shaped member 120 attached to the upper end of the legs 79. The walking beam 83 is pivotally mounted at 121 on a member 122 suitably attached to the upper end of the piston rod. A coil spring 123 surrounds the piston rod and is supported by an adjustable member 124 in a position to abut the lower end of the sleeve 120 and cushion the piston at the ends of its upward strokes. A pump 126, like that shown in Fig. 10, is connected to a member 127 attached to and extending laterally from the lower end of the cylinder. A link 128 is pivotally connected to the piston of the pump 126 and to a bell crank

arm 129 which is pivotally mounted on a member 130 attached to the cross member 117. A rod 131 is connected to the bell crank arm and has a sliding connection with a member 132 pivotally connected to the walking beam. As the beam is driven, the sliding connection between member 132 and rod 131 permits vertical movement of the beam, but transmits a rocking motion to the bell crank arm which drives the pump piston through link 128. In operation of the pump, air and liquid are pumped, respectively, from the atmosphere and tank 133 through a conduit 134 opening into the lower end of the cylinder bore. Liquid escaping between the walls of the cylinder and piston enters a groove 136 and is conducted by a conduit 137 to the tank. On predetermined upward movement of the piston 118, pressure fluid escapes through a pipe connection 138, the groove 136, conduit 137 and to atmosphere through a vent 139 in the top of tank 133.

In Figures 12, 13 and 14 there is shown a modified form of guiding structure for guiding the reciprocatory movements of the piston rod 16. In this structure the piston rod is threaded at its upper end into an opening in a plate 140 attached, as by bolts 141, to a crosshead 142. The legs of the supporting structure 4 are bent to form parallel upper portions 144, and connected to each of these portions, as by rivets, is a guide member 145 that reciprocably engages the crosshead 142 as shown in Fig. 14. Supported by the crosshead is a pivot pin 146 that pivotally supports a member 147 to which the walking beam 5 is attached. Formed in the crosshead is a chamber 148 that is connected to atmosphere at its upper end at points adjacent each guide member 145 by vent ports 149. The hose 36 communicates with the chamber 148 at its lower end. During operation of the pump, air carrying liquid in the form of mist is forced through the hose 36 to the chamber 148 and is vented to atmosphere through the ports 149. Part of the liquid condenses as it passes through the vent ports, and lubricates the guide members. When the pumping system is shut down the chamber 148 acts as a storage chamber for liquid escaping through the hose 36.

As a result of this invention, it will be noted that an improved yielding supporting structure for a walking beam has been provided. It will further be noted that there has been provided with the supporting structure an improved means for building up the yielding force automatically to a value sufficient to support the walking beam and its loads, and for maintaining the force at the necessary values. It will further be evident that there is obtained a sealing and a lubrication of the moving parts by a liquid in an improved manner. Other uses and advantages of the improved supporting structure will be clearly apparent to those skilled in the art.

While there are in this application specifically described several forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A yieldable supporting structure adapted for association with a well pumping apparatus of the kind embodying a walking beam, comprising, in combination, means adapted to yieldingly sup-

port a walking beam and including a cylinder containing a reciprocatory piston, means for connecting said piston to the walking beam, passage means for connecting a substantial volume of air under pressure exceeding atmospheric in communication with the lower end of said cylinder, means for venting said cylinder to atmosphere at a point spaced from its upper end, said piston moving upwardly under the action of the air pressure when the load on the walking beam is reduced, effecting a closure of said venting means and an increase in pressure at the upper end of said cylinder, and valve controlled passage means for delivering fluid from the upper to the lower end of said cylinder when the pressure at its upper end exceeds the pressure at its lower end.

2. A yieldable supporting structure adapted for association with a well pumping apparatus of the kind embodying a walking beam, comprising, in combination, means adapted to yieldingly support a walking beam and including a cylinder containing a reciprocatory piston, means for connecting said piston to the walking beam, an enclosed tank containing air at a relatively high pressure, means for connecting said tank freely in communication with the lower end of said cylinder, a vent opening into said cylinder at a point spaced from its upper end for connecting said cylinder to atmosphere, said piston moving upwardly under the action of the air pressure when the load on the walking beam is reduced, covering said vent and compressing air within the upper portion of said cylinder, and valve controlled passage means for delivering fluid from the upper to the lower end of said cylinder when the pressure within the upper end exceeds the pressure in the lower end.

3. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting said piston to the walking beam, passage means for connecting a substantial volume of air under pressure exceeding atmospheric in communication with the interior of said hollow piston, the lower portion of said cylinder and said piston cooperating to form a chamber space adapted to contain a volume of liquid for continuously sealing the lower end of said piston against the escape of air from within the latter, means including a piston controlled vent passage for connecting the upper end of said cylinder to atmosphere, said piston moving upwardly on reduction of load on the walking beam and effecting closure of said vent passage and an increase in pressure at the upper end of said cylinder, and valve controlled passage means for delivering fluid from the upper to the lower end of said cylinder when the pressure at its upper end exceeds the pressure at its lower end.

4. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting said piston to the walking beam, passage means for connecting a substantial volume of air under pressure exceeding atmospheric in communication with the interior of said hollow piston, the lower portion of said cylinder and said piston cooperating

5 to form a chamber space adapted to contain a volume of liquid for continuously sealing the lower end of said piston against the escape of air from within the latter, means including a vent port opening into said cylinder at a point spaced from its upper end for venting the upper portion of said cylinder to atmosphere, said piston moving upwardly under the action of the air pressure when the load on the walking beam is reduced, covering said vent port and compressing air in the upper end of said cylinder, and valve controlled passage means connecting the upper and lower ends of said cylinder for delivering fluid from the upper to the lower end of said cylinder when the pressure at its upper end exceeds the pressure at its lower end.

20 5. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting said piston to the walking beam, the lower portion of said cylinder and said piston cooperating to form a chamber space adapted to contain a volume of liquid for continuously sealing the lower end of said piston against the escape of air from within the latter but insufficient to fill the space within said piston when the latter is in its lowermost position, means including a conduit opening through the lower end of said cylinder and extending above the level of said liquid for connecting the space within said piston above the liquid to a substantial volume of air under pressure exceeding atmospheric, means including a piston controlled vent passage for connecting the upper end of said cylinder to atmosphere, said piston moving upwardly under the action of the air pressure when the load on the walking beam is reduced and, on a predetermined upward movement of said piston, closing said vent passage and compressing fluid within the upper end of said cylinder, and valve controlled passage 30 means for delivering fluid from the upper to the lower end of said cylinder when the pressure at its upper end exceeds the pressure at its lower end.

45 6. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting said piston to the walking beam, means for connecting the interior of said piston in communication with a volume of air under pressure exceeding atmospheric, the lower portion of said cylinder and said piston cooperating to form a chamber space adapted to contain a volume of liquid for continuously sealing the lower end of said piston against the escape of air from within the latter, means for cushioning said piston as the latter moves toward the lower end of said cylinder, said cushioning means including a radially extending flange formed around the lower end of said piston and a space of decreasing cross sectional area at the lower end of said cylinder within which said flange moves and partially entraps liquid, means for venting the upper end of said cylinder to atmosphere, said piston moving upwardly under the action of the air pressure when the load on the walking beam is reduced, cutting off communication of said venting means

with said cylinder after predetermined movement and compressing fluid within the upper end of the latter, and valve controlled passage means for delivering fluid from the upper to the lower end of said cylinder when the pressure within its upper end exceeds the pressure within its lower end.

7. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting said piston to the walking beam, the lower portion of said cylinder and said piston cooperating to form a chamber space adapted to contain a volume of liquid for continuously sealing the lower end of said piston against the escape of air from within the latter but insufficient to fill the space within said piston when the latter is in its lowermost position, means including a conduit opening through the lower end of said cylinder and extending above the level of said liquid for connecting the interior of said piston in communication with a volume of air under pressure exceeding atmospheric, and means for venting the upper end of said cylinder.

8. A yieldable supporting structure adapted for association with a well pumping apparatus of the kind embodying a walking beam, comprising, in combination, means adapted to yieldingly support a walking beam and including a cylinder containing a reciprocatory hollow piston open at its lower end, means for connecting the piston to a walking beam, the lower portion of said cylinder and said piston cooperating to form a chamber space adapted to contain a volume of liquid for sealing the lower end of said piston against the escape of pressure fluid from within the latter during normal reciprocation in said cylinder, said hollow piston providing a space above said liquid for storing a gaseous fluid under pressure, means including a reservoir open to atmosphere and communicating with the upper portion of said cylinder at a point spaced from its upper end for collecting liquid escaping upwardly past said piston, said piston moving upwardly on reduction of load on the walking beam, cutting off communication with said reservoir and trapping liquid within the upper portion of said cylinder, and valve controlled passage means for delivering liquid from the upper to the lower end of said cylinder when the liquid trapped within the upper end is subjected to pressure by the upward movement of said piston.

9. A yieldable supporting structure adapted for association with a well pumping apparatus of the kind embodying a walking beam, comprising, in combination, a cylinder, a hollow piston open at its lower end reciprocable within said cylinder and having a piston rod pivotally connected when in use to a walking beam, means for slidably guiding said piston rod, a chamber within said piston rod, means for normally venting said chamber to atmosphere at points in said piston rod above said guiding means, passage means connecting said chamber in communication with the upper portion of said cylinder, and means for connecting the space within said hollow piston in communication with a volume of air under pressure exceeding atmospheric, the lower portion of said cylinder and said piston cooperating to form a chamber space adapted to contain a

volume of lubricating liquid for sealing the air within said hollow piston, the lubricating liquid being forced gradually past said piston by air pressure to the upper portion of said cylinder where it is carried by air escaping through said venting means to effect a lubrication of said piston rod.

10. A yieldable supporting structure adapted for association with a well pumping apparatus of the kind embodying a walking beam, comprising, in combination, a cylinder, a hollow piston open at its lower end reciprocable within said cylinder and having a piston rod pivotally connected when in use to a walking beam, means for slidably guiding said piston rod, a chamber within said piston rod, means for normally venting said chamber to atmosphere at points above said guiding means, passage means connecting said chamber in communication with said cylinder at a point spaced from the upper end of the latter, means for connecting the space within said hollow piston in communication with a volume of air under pressure exceeding atmospheric, the lower portion of said cylinder and said piston cooperating to form a chamber space adapted to contain a volume of liquid for sealing the air within said hollow piston, said piston moving upwardly under the action of the air pressure when the load on the walking beam is reduced, cutting off communication between said cylinder and said passage means and compressing air within the upper portion of said cylinder, and valve controlled passage means opening through the upper end of said cylinder and communicating with the latter adjacent its lower end for delivering fluid from the upper to the lower end of said cylinder when the pressure at its upper end exceeds the pressure at its lower end.

11. A yieldable supporting structure adapted for association with a well pumping apparatus of the kind embodying a walking beam, comprising, in combination, a cylinder, a piston reciprocable within said cylinder and having a piston rod pivotally connected when in use to a walking beam, means including a vent port opening into said cylinder at a point spaced from its upper end for normally venting the upper portion of said cylinder freely to atmosphere, means including a valve opening toward said cylinder for connecting the upper end of the latter to atmosphere, means for connecting the lower portion of said cylinder in communication with a volume of air under pressure exceeding atmospheric, said piston moving upwardly under the action of air pressure when the load on the walking beam is reduced, overrunning said vent port and compressing air within the upper portion of said cylinder, and valve controlled passage means carried by said piston for delivering fluid from the upper to the lower end of said cylinder when the pressure at its upper end exceeds the pressure at its lower end.

12. A yieldable supporting structure adapted for association with a well pumping apparatus of the kind embodying a walking beam, comprising, in combination, a cylinder, a piston reciprocable within said cylinder and having a piston rod pivotally connected when in use to a walking beam, means including a vent port opening into said cylinder at a point spaced from its upper end for normally venting the upper portion of said cylinder freely to atmosphere, means including a valve opening toward said cylinder for connecting the upper end of the latter to atmosphere, means for connecting the lower portion of said

cylinder in communication with a volume of air under pressure exceeding atmospheric, said piston moving upwardly under the action of air pressure when the load on the walking beam is reduced, overrunning said vent port and compressing air within the upper portion of said cylinder, and means including valve controlled passage means opening through the upper end of said cylinder and communicating with the latter adjacent its lower end for delivering fluid from the upper to the lower end of the cylinder when the pressure at its upper end exceeds the pressure at its lower end.

13. A yieldable supporting structure adapted for association with a well pumping apparatus of the kind embodying a walking beam, comprising, in combination, relatively reciprocable cylinder and piston elements, means for connecting

one of said elements to a walking beam, means for connecting one end of said cylinder in communication with a volume of air under pressure exceeding atmospheric whereby the element connected to the walking beam is yieldably supported, means including a port opening into said cylinder at a point spaced from the other end of the latter for venting the other end of said cylinder to atmosphere, said element connected to the walking beam moving upwardly when the load on the latter is reduced, effecting a closure of said vent port and a compression of air in said other end of said cylinder, and valve controlled passage means for delivering fluid from said other end to said first mentioned end of said cylinder when the pressure therein exceeds the pressure in said first mentioned end.
